UNITED STATES PATENT OFFICE

115,824

DESIGN FOR A FIRE EXTINGUISHING GRENADE

William Louis Roessner, Chicago, Ill., assignor to
Bertha L. MacGregor, as trustee

Application May 22, 1939, Serial No. 85,127

Term of patent 14 years

To all whom it may concern:

Be it known that I, William Louis Roessner, a citizen of the United States, residing at Chicago, in the county of Cook and State of Illinois, have invented a new, original, and ornamental Design for a Fire Extinguishing Grenade, of which the following is a specification, reference being had to the accompanying drawing, forming part thereof.

In the drawing:

Fig. 1 is a front elevation of a fire extinguishing grenade showing my new design.

Fig. 2 is a rear elevation of the same.

Fig. 3 is a top plan view of the same.

I claim:

The ornamental design for a fire extinguishing grenade, as shown.

WILLIAM LOUIS ROESSNER.
